UNITED STATES PATENT OFFICE.

ROBERT H. SHELTON, OF CELESTE, TEXAS.

COT-FRAME.

947,133.

Specification of Letters Patent. Patented Jan. 18, 1910.

Application filed September 14, 1909. Serial No. 517,668.

To all whom it may concern:

Be it known that I, ROBERT H. SHELTON, a citizen of the United States, residing at Celeste, in the county of Hunt and State of Texas, have invented a new and useful Cot-Frame, of which the following is a specification.

The objects of the invention are, generally, the provision in a merchantable form, of a device of the above-mentioned class, which shall be inexpensive to manufacture, facile in operation, and devoid of complicated parts; specifically, the provision of a cot adapted to accommodate two persons, means being provided for dividing the cot into two separate sleeping compartments, the cot being so constructed that it may readily be folded into compact form for storage; other and further objects being made manifest hereinafter as the description of the invention progresses.

The invention consists in the novel construction and arrangement of parts hereinafter described, delineated in the accompanying drawings, and particularly pointed out in that portion of this instrument wherein patentable novelty is claimed for certain distinctive and peculiar features of the device, it being understood, that, within the scope of what hereinafter thus is claimed, divers changes in the form, proportions, size, and minor details of the structure may be made, without departing from the spirit or sacrificing any of the advantages of the invention.

Like numerals of reference are employed to denote corresponding parts throughout the several figures of the drawings.

In the accompanying drawings, Figure 1 shows the invention in perspective; Fig. 2 is an end elevation of the cot extended; Fig. 3 is an end elevation of the cot folded; Fig. 4 is a detail perspective of the hinge.

The sides of the cot comprise corner posts 3, connected, intermediate their ends, by longitudinal beams 2, T plates 4 or other means adapted to a like end, constituting the connecting elements between the beams 2 and the posts 3. The inner faces of the posts 3 slightly below the beams 2 are notched to form shoulders 5, the upper faces of which are inclined downwardly, the upper surfaces of the notches being rounded as denoted by the numeral 20.

Located at either end of the structure and

constituting a connection between the sides, are cross pieces. These cross pieces comprising sections 6, are united with the posts 3 by means of links 7, the outer ends of which are pivoted to the posts 3 slightly above the notches therein, the inner ends of the links 7 being pivotally connected with the intermediate portions of the sections 6. The remote ends of the sections 6 are adapted to rest upon the beveled upper faces of the shoulders 5, the said remote ends being beveled as denoted by the numeral 8, to engage the corner posts 3. The adjacent ends of the sections are disposed above the plane of their remote ends, and beveled as denoted by the numeral 9 to engage each other. The adjacent ends of the sections 6 are united by hinges 10. These hinges 10 comprise arms 11 which are secured to the lower faces of the sections 6 in any suitable manner, the adjacent ends of the arms being pivotally united with the depending U shaped central portion 12. This central portion 12 is adapted to serve as a support for the pole 14, connecting the cross pieces at one end of the device with those at the other end. A connecting element, in the present instance shown in the form of an eye bolt 15 extends upwardly through the central portion 12 of the hinge into engagement with the end of the pole 14. Eye bolts 19 are mounted in the posts 3, a flexible member 17, preferably a light chain, connecting the eye bolts. The intermediate portion of the flexible member 17 is connected with the eye bolt 16 by a rigid member 16. A piece of canvas 18, or the like is mounted upon the beams 2, its intermediate portion being supported upon the pole 14, which, when the device is ready for use, is disposed in substantially the same plane as the beams 2. By means of this centrally disposed pole 14, the canvas is made to sag slightly between the pole and the beams 2 to form two separate sleeping compartments.

When the device is in condition for use, the upwardly extending section 6 of the cross pieces, taken with the flexible member 17 and the rigid element 16 form a truss of simple but efficient construction, whereby the rigidity of the structure is promoted. By raising the pole 14 the remote ends of the sections 6 of the cross pieces may be lifted from the shoulders 5 whereon they are supported, and permitted to drop, through the

peculiar connection afforded by the links 7, into parallelism with the corner posts 3, the hinges 10 permitting the sides to be brought into close relation with each other, the device, in the present instance, presenting the compact form shown in Fig. 3.

Hooks 22 terminately pivoted to the posts 3 and engaging eyes 23 on the cross pieces 6 may be employed to stiffen the structure 10 when in use, and to prevent the pillows from falling from the end of the cot.

Having thus described my invention, what is claimed is:

1. A cot comprising corner posts having shoulders upon their adjacent faces; a cross piece including sections pivotally connected at their adjacent ends and having their remote ends removably supported upon the shoulders; and links pivotally connecting 20 the sides with the adjacent sections of the cross piece.

2. A cot comprising sides; a cross piece including sections having their remote ends removably receivable by the sides; a hinge 25 uniting the adjacent ends of the sections; links pivotally connecting the sides with the adjacent sections of the cross piece; a flexible element uniting the sides below the cross

piece; and a rigid member uniting the flexible element with the hinge.

30

3. A cot comprising sides; a cross piece including sections pivotally connected at their adjacent ends and having their remote ends removably receivable by the sides; links pivotally connecting the sides with the adjacent sections of the cross piece; and hooks detachably securing the sections to the sides, above the links.

35

4. A cot comprising sides; cross pieces located at the ends of the sides and comprising sections having their remote ends removably receivable by the sides; hinges uniting the adjacent ends of the sections; links pivotally connecting the sides with the adjacent sections of the cross piece; flexible elements 45 uniting the sides below the cross pieces; rigid members uniting the flexible elements with the hinges; and a pole terminally supported in the hinges.

40

In testimony that I claim the foregoing as 50 my own, I have hereto affixed my signature in the presence of two witnesses.

ROBERT H. SHELTON.
